Primary Examiner — Rhea Shields

(57) **CLAIM**

The ornamental design for a toothbrush handle, as shown and described.

DESCRIPTION

FIG. 1 is a perspective view showing my design;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof; and,
 FIG. 7 is a bottom plan view thereof.
 In the drawings, the broken lines are for the purpose of illustrating portions of the toothbrush handle and forms no part of the claimed design.
